ELECTRICAL TRANSLATING DEVICE

Filed Oct. 17, 1923

Inventor:
Stanley S. A. Watkins,

by *E.W. Adams, Atty.*

UNITED STATES PATENT OFFICE.

STANLEY S. A. WATKINS, OF NEW YORK, N. Y., ASSIGNOR TO WESTERN ELECTRIC COMPANY, INCORPORATED, OF NEW YORK, N. Y., A CORPORATION OF NEW YORK.

ELECTRICAL TRANSLATING DEVICE.

Application filed October 17, 1923. Serial No. 669,021.

This invention relates to electrical translating devices. It is a well known characteristic of vibrating bodies such as diaphragms that when equal driving forces are applied to them at different frequencies, a greater response or amplitude of vibration will be produced at some frequency than at others. This frequency is usually known as the natural frequency of the diaphragm. The variation in response at different frequencies results in distortion. It has been found that by the application of damping to the vibrating body or diaphragm, its natural frequency or natural period may be altered and the distortion over a given range of frequencies consequently reduced or substantially eliminated.

This invention applies a new damping agent to the vibrating parts of an oscillograph for the purpose of eliminating distortion.

An object of this invention is to produce undistorted reproductions of the wave forms of electric currents or electromotive forces. Another object of the invention is to translate electrical variations into impulses perceptible to the senses and to cause these impulses to give a true representation of the electrical variations. A further object of this invention is to alter the natural frequency of vibrating reeds driven in accordance with varying electric energy by applying air damping thereto.

A feature of this invention relates to a method of mounting a light reflecting element between two vibratory portions of an oscillograph in such manner that air damping may be applied and flexibility may be secured.

Another feature of this invention relates to an oscillograph element arranged to utilize electrostatic force as means for actuating its vibratory elements.

A still further feature relates to an oscillograph element utilizing magnetic forces as a means for actuating its vibratory members and having means for adjusting the reluctance of its magnetic circuit.

The objects of the invention may be accomplished by arranging the vibrating portions of an oscillograph element which may comprise, two vibrating members or reeds as for example, diaphragms adjacent to two fixed plates. The vibrating members are so positioned with respect to the fixed plates

that a very thin film of air remains therebetween. Additional means comprising a very small mirror is flexibly connected to the adjacent edges of the vibrating diaphragm for causing deflections in a beam of light which may be reflected upon a sensitized film. Means is also provided for exerting a driving force upon the vibratory elements and this driving force is preferably applied in accordance with the variations of an electric current through the medium of an electrostatic or magnetic field.

The drawings to which reference is made in the detailed description which follows are illustrative of embodiments and details of this invention as follows:

Fig. 1, a vertical section of an oscillograph element employing magnetic driving means.

Fig. 2, a plan view of the device of Fig. 1.

Fig. 3, a perspective view of a mirror mounting.

Fig. 4, an adjustable air gap, magnetically-driven oscillograph element.

Fig. 5, a plan view of the device of Fig. 4.

Fig. 6, an oscillograph with rectangular diaphragms and suspension mounting.

Fig. 7, a plan view of the device of Fig. 6.

Fig. 8, an electrostatically driven oscillograph.

Fig. 9, a plan view of Fig. 8.

Fig. 10, a practical application of the oscillograph of this invention.

Throughout the various figures of the drawing like reference characters have been used to denote like members.

Referring to Figs. 1 to 3, two halves 10 and 11 of a split circular diaphragm are arranged in the same plane and adjacent to an annular plate 12 whereby a thin film of air at 14 and 15 is maintained for the purpose of damping. Mounted upon the semi-circular diaphragms 10 and 11 is a mirror 16. The diaphragms 10 and 11 are, in this instance, preferably of magnetic material. The damping plate 12 may be of any desired material preferably nonmagnetic, for example, brass. Adjacent to the diaphragms 10 and 11 is placed a three-pole electromagnet 17. This magnet comprises a core 20 which is laminated or otherwise constructed so as to reduce energy losses therein, and windings 21, 22 and 23.

The diaphragms 10 and 11, the damping plate 12 and the magnet 17 are held in their proper positions in a case 26 having a screw

cap 27. The case and cap are preferably made of insulating material, such as bakelite or hard rubber.

The energizing coils 21, 22 and 23 are wound upon the respective poles of magnet 17. The winding 22 which is on the middle pole is connected to a source of direct current 24 which causes the core 20 to be normally polarized so that the middle pole has one polarity and the other two poles the opposite polarity.

Windings 21 and 23 on the other respective poles of magnet 17 are connected preferably in series to a source of varying electromotive force or current 28 in such manner that when electric current flows therethrough, the magnetic field set up by one winding will aid the magnetic field of winding 22 and the field set up by the other 20 winding will oppose the field of winding 22.

A mirror 16 is flexibly attached to a pair of parallel wires or threads 30 and 31 in any well known manner, as, for example, by means of wax, mucilage, or gum. The wires 25 supporting mirror 16 are soldered or otherwise attached to the two diaphragms 10 and 11.

Fig. 3 is a perspective view of another mounting for the mirror 16. The wires 30 and 31 are attached to posts 32 fixed to the diaphragms 10 and 11. The mirror is thereby raised above the diaphragms so that the gap between the diaphragms may be reduced, if desired.

In Fig. 1, when the source of varying electromotive force is connected at 28 as shown, the current in windings 21 and 23 is caused to vary and produce a corresponding variation in the magnetic field of core 20. Accordingly, the force exerted on diaphragms 10 and 11 produces vibration thereof. In order that the amplitude of this vibration shall be proportional to the amplitude of the current in windings 21 and 23, the thin 45 film of air 15 is maintained adjacent to the diaphragms 10 and 11. This thin film of air is preferably given such dimensions as to provide the required damping action upon the vibrating parts. Since the windings 21 and 23 produce opposite poles, their action in causing deflection of diaphragms 10 and 11 will be in opposite senses; i. e., when the diaphragm 10 moves toward magnet 17, diaphragm 11 will move away from it. This 55 motion of the diaphragms produces a deflection of mirror 16 which is proportional to the added deflection of both diaphragms.

Another form which the oscillograph element of this invention may take is shown in Figs. 4 and 5 wherein the central pole 35 of magnet 17 is adjustable by means of screw 36 acting in a slot 37. In this figure, the polarizing winding 22 is shown divided and positioned on the outer poles of the magnet 17. The damping plates 36 and 37 and

the reeds or diaphragms 38 and 39 which are all rectangular in shape are attached to the core of the magnet 17 by means of screws.

The mirror 16 is mounted in the manner described in Fig. 2 between the rectangular vibratory reeds 38 and 39.

In the oscillograph of Fig. 6, two rectangular diaphragms 38 and 39 are suspended in front of the poles of magnet 17 upon parallel wires 40 and 42 and 41 and 43, respectively, lying in the same plane.

In the plan view shown in Fig. 7 the plates 36 and 37 are omitted to show the form of the mounting of the reeds 38 and 39 more clearly. Wires 40 and 41 are preferably 80 rigid, whereas wires 42 and 43 are preferably resilient to allow vibration of the diaphragms about the wires 40 and 41 as axes. The mirror 16 is positioned between slots in the adjacent edges of diaphragms 38 and 39. It is attached to wires 42 and 43 in the manner already described.

Figs. 8 and 9 illustrate a form of electrostatic oscillograph. The vibrating elements or diaphragms 10 and 11 are damped by the 90 air films 14 and 15 maintained by the conducting plate 45. The diaphragms 10 and 11 are insulated from conducting plate 45 by an insulating washer 46. A mirror 16 is flexibly attached to the diaphragms 10 95 and 11 across the gap between them.

Diaphragms 10 and 11 are connected in parallel branches of an electric circuit including the secondary 47 of a transformer 48 differentially connected to one terminal of 100 a battery 49. The opposite terminal of the battery connects to the conducting plate 45. A primary 50 of transformer 48 is connected to leads arranged to be connected to a source of varying electromotive force or 105 current.

The electromotive force set up in the secondary 47 by a change of current in the primary 50 produces a potential difference between the diaphragms 10 and 11 and the 110 conducting plate 45 respectively one of which opposes that produced by battery 49 and the other aids it. Thus one diaphragm is drawn from its normal position toward the plate 45 whereas the other diaphragm 115 moves from its normal position in a direction away from plate 45. Thus the movement of the diaphragms in opposite directions is additive in deflecting mirror 16.

Fig. 9 which is a plan view of the device of Fig. 8 needs no additional explanation.

Referring to Fig. 10, block 51 represents a source of variable electromotive force or current, as, for example, a battery and transmitter, connected to the windings 21 and 23 of a device such as shown in Fig. 1. The electric current produced by the device 51 effects the operation of oscillograph element 52 in the manner already described, whereby deflections of mirror 16 in accordance 130

therewith, are produced. A suitable source 59 preferably of monochromatic light is concentrated by a suitable lens system 60 into the parallel beam 61 and reflected by the 6 mirror 16, upon the narrow slit 62, through which it passes to fall upon the film 63, which is sensitized with a suitable photographic emulsion. As the mirror is actuated in accordance with the variations of 10 source 51, the beam of light is deflected so that a greater or lesser portion of it passes through the slit 62 to the film 63.

The motion of mirror 16 is such as to cause the reflected beam of light to move 15 transversely with respect to the direction of longitudinal movement of the strip of photographic emulsion and to move in such manner that the beam of light, as a brush will cover only one-half of the width of the 20 strip when the light beam is stationary, whereas, when in transverse motion, the light beam will cover more or less of the width of the photographic emulsion by an amount proportional to the momentary current supplied to the distortionless translating device 52. The photographic strip 63 is unwound from the reel 64, past the slit 62, upon another reel 65, where it is stored until its development. The width of the 25 slit 62 that is its dimension in the direction of motion of the film is small as compared with the variations in the photographic records which are to be recorded and which correspond to the frequencies of the source 30 51. In other words, the width of the slit is made so narrow that the time required for a given point on the photographic emulsion to pass across the opening of the slit is a small fraction of the time of the cycle of 35 the maximum frequency of source 51, which is to be recorded. The strip 63 with its photographic emulsion, may consist of a strip of paper, celluloid or any other suitable material that may be found most convenient.

It is not intended that the invention herein disclosed shall be limited to the specific embodiments described but only by the appended claims.

60 The invention claimed is:

1. In an oscillograph, in combination, a

pair of magnetic vibratory armatures, electromagnetic means responsive to current variations to be detected for deflecting the armatures in opposite directions, and a mirror adapted to be vibrated in accordance with cumulative movement of the armatures. 65

2. In an oscillograph in combination, a pair of clamped magnetic armatures having 60 their free edges adjacent to but separated from each other, means for oppositely polarizing said armatures, electromagnetic means responsive to current variations to be detached for deflecting the armatures in opposite directions, and a mirror flexibly mounted to the free edges of said armatures and adapted to be vibrated in accordance with the cumulative movement of the armatures. 65

70 3. The combination in an oscillograph device of an electromagnet having a plurality of windings, means for energizing one of said windings by direct current, and means for connecting a source of electromotive force to be analyzed to another of said windings whereby a magnetizing force opposing that produced by the winding energized with direct current is produced, a plurality of diaphragms adjacent to said electromagnet driven in accordance with variations in the resultant magnetizing force, and means adjacent to said diaphragms for producing a thin film of air upon the surface thereof to equalize the response of said diaphragms 80 to different frequencies. 85

4. In combination, a source of current, means for producing variations in the wave form of current flowing from said source, a pair of vibratory diaphragms actuated in 90 opposite directions in accordance with the variations of the current, a mirror adapted to be moved in response to the cumulative movement of the diaphragms, and damping means for the diaphragms to prevent distortion of the wave form at frequencies corresponding to the natural frequencies of the diaphragms. 95

In witness whereof, I hereunto subscribe my name this 10th day of October A. D., 100 1923.

STANLEY S. A. WATKINS.
